UNITED STATES PATENT OFFICE.

MICHAEL SEGEL, OF NEW YORK, N. Y., ASSIGNOR TO ELIZABETH MEHLFELDER
UEBELMESSER, OF BAYSIDE, NEW YORK.

SELF-THREADING DEVICE FOR MOTION-PICTURE APPARATUS.

1,225,184.

Specification of Letters Patent.

Patented May 8, 1917.

Application filed January 14, 1914. Serial No. 312,055.

To all whom it may concern:

Be it known that I, MICHAEL SEGEL, a citizen of the United States, residing at New York city, county and State of New York, have invented certain new and useful Improvements in Self-Threading Devices for Motion-Picture Apparatus, of which the following is a clear, full, and exact description.

10 This invention relates to that general class of self threading machine referred to in my application Serial No. 774,304, filed June 18th, 1913, and has for its object to provide means between the feeding sprocket and the 15 reel to be exhibited to cause the film upon the mere rotation of its reel to be delivered to the sprocket wheel or other advancing device to thread it by means of the threading mechanism through the exhibiting portion 20 of the machine, and also to cause the automatic delivery of the film after exhibition on to the receiving reel, where it will be grasped and wound up without any other action on the part of the operator, excepting 25 placing an empty reel in place and placing the reel to be exhibited in place in the machine, and operating the driving mechanism.

In order to accomplish these features I supply preferably a spring control pivoted 30 guide boot or chute, which extends from the first sprocket roller, the upper ends of the chute having a flaring mouth and fitting nicely between the two flanges of the reel, so that the free end of the film as the reel is 35 rotated will enter the chute, pass down the chute and be guided with its perforations into contact with the teeth of the sprocket roller, and by them forwarded through the machine, making the proper loops as referred to in my aforesaid application for 40 patent, and after exhibition be delivered by preferably a sprocket roller to a second downwardly depending chute or boot, which has its end in proximity to the shaft of the 45 receiving reel, being mounted between the flanges of the reel and having cut-out portions at the lower end of the boot, permitting the free rotation of the film clamps which will be referred to hereinafter, which

are formed of springs fastened on the shaft 50 of the reel, so that the film, as it travels down the boot, will be directed to the spring by the boot itself, and caught under the spring so that upon the rotation of the shaft the exhibited film will be wound up as in 55 ordinary practice.

In the drawings:

Figure 1 is a vertical sectional view of an embodiment of my invention.

Fig. 2 is a detail sectional view of the 60 orifice plate, advancing sprocket and a portion of the loop receptacles, the section being taken on a line 2—2 in Fig. 1.

Fig. 3 is a detail view of the lower or take-up roll and film guide adjacent thereto. 65

As herein illustrated a motion picture machine casing is indicated by the numeral 1 and is provided with the usual aperture 2 and orifice plate 3 adjacent thereto.

In the upper part of the device I mount 70 the filled reel 4 in the usual manner, and in the lower part the take-up reel 5; to take the film from the upper reel, pass it downwardly across or between the openings 2 and 6 on to the take-up reel automatically is the 75 object of the device, the said operation being accomplished as follows:

To thread the device, the upper reel 4 is unwound until the film engages the sprocket 7, the film passing through the guide chute 80 8, which is pivotally mounted on the shaft 9 of the sprocket 7.

A continued rotation of the reel 4 forces the film through the curved channel 10 between the apertures 2 and 6 thence through 85 the channel 11 into the box 12 from which the film passes into the guide chute 13, thence to the take-up reel 14. During its course the film will engage the intermittent sprocket 15 and advancing sprocket 16. 90 The mechanism indicated by 17 is a dia-grammatic illustration of the operating mechanism for the device. Like the chute 8, the chute 13 is pivotally mounted on the shaft 18 and is adapted to swing upwardly 95 as the roll of film on the take-up reel increases in size (see dotted lines 19, Fig. 1). To automatically engage the take-up reel 1

provide clips or devices to grasp the end of the reel, such devices being herein indicated by 20 and consist of resilient fingers mounted on the shaft 18. When the free end of the film reaches the shaft 18 it will slide into the gap 21 and become pinched by the resilient fingers; at this time all of the running parts will be running at the same speed, hence the film will be carried around by the 10 rotating shaft 18. The guide 8 will move inwardly, as the roll of film on the upper reel decreases in diameter, by virtue of the pull of the spring 21 (see dotted lines 8).

15 The chute 13 rests by gravity upon the roll of film on the take-up reel.

18 Adjacent the sprockets 15 and 16 I locate guides 22 and 23 to guide the film into and out of the box 12. By virtue of the arrangement of the chutes 8 and 13, they will always 20 remain in proper relationship with respect to the reels 4 and 14.

25 Although mere manual rotation of the full reel is sufficient to cause the end of the film to enter the upper end of the guiding chute, I prefer to mount a slight friction drive on the shaft of the upper reel and connect it by chain or other means with the mechanism of the machine to cause it to start at slow speed in order that the end of 30 the film may be made to enter the chute. After the film is taken up by the chute the major part of the drive on the upper reel is accomplished by the tooth sprocket wheel, which rotates the reel much faster by its 35 mere pull than initial starting driving mechanism.

I claim as my invention:

1. In combination with a film advancing mechanism of a motion picture apparatus, 40 a roll of film, a support therefor, a guide for the film mounted in close proximity to the outer surface of the roll of film whereby on the rotation of the film roll the free end of the film is caused to enter said guide 45 and directed by said guide to the feeding mechanism in the motion picture apparatus.

2. The combination of a roll of film and a feed sprocket, a supporting frame for the same, a film guiding device interposed between the roll of film and the feed sprocket for the purpose of guiding and directing the free end of the film into said guide and from the delivery reel on to the feed sprocket in a motion picture apparatus automatically. 50

55 3. The combination of a driven film reel and a sprocket mounted in a film manipulating apparatus, and a guide mounted between the roll of film and a feed sprocket to catch the film for automatic delivery to the feed sprocket.

60 4. The combination of a roll of film, a feed sprocket, a guide mounted between the roll of film and the feed sprocket for the

purpose of receiving and delivering a film from the feed sprocket to a film receiving 65 roll after the film has passed through the film manipulating apparatus or motion picture apparatus.

5. In a motion picture apparatus, a delivery reel and a feed sprocket, a device consisting of a guide funnel interposed between the delivery reel and the feed sprocket to catch the free end of a film from the delivery reel and deliver it automatically to a feed sprocket in a motion picture apparatus 75 substantially as described.

6. In a motion picture apparatus, a lower feed sprocket and a receiving reel, a guide for the film interposed between said sprocket and said receiving reel to deliver the free 80 end of a film into said reel, and an arrangement on the hub of said reel to grasp the free end of a film for the purpose of winding it on a hub automatically and during 85 rotation of said reel.

7. In a motion picture apparatus, a frictionally driven delivery reel, a feed sprocket, a swingable guide chute between said delivery reel and said feed sprocket to receive 90 a film for automatic delivery to said feed sprocket substantially as described.

8. In a motion picture apparatus, a lower feed sprocket and a receiving reel, a swingable guide chute interposed between the hub of the receiving reel and said feed 95 sprocket, a device on said reel hub to co-operate with the film guide to automatically catch the film on said reel hub substantially as set forth.

9. In a motion picture apparatus, a roll 100 of film, a feed sprocket, a guide interposed between said roll of film and said feed sprocket and an automatic film catch on the hub of the film roll to automatically deliver a film from one on to the other by the mere rotation of said feed sprocket and said film roll.

10. In a motion picture apparatus, a lower feed sprocket, a receiving reel, a film clasping means on the hub of said reel, a guide 110 chute interposed between said feed sprocket and said reel to automatically deliver a free end of film from said feed sprocket to the clasping device on the hub of said film winding reel.

11. A motion picture apparatus consisting of at least two feed sprockets and two film reels, guides interposed or located between said feed sprockets and said film rolls to automatically catch the free end of a film 120 and deliver it from one to the other upon the mere rotation of said feed sprockets and film rolls.

12. In a film manipulating apparatus or the like, a film reel thereon, a feed sprocket 125 adjacent thereto, a device mounted between

said reel and said sprocket, consisting of guides for the film between said delivery member and said receiving member, a projection or catch on the receiving member to engage the approaching free end of a film upon and during operation of the apparatus substantially as described.

Signed at New York city, New York, this
10th day of January, 1914.

MICHAEL SEGEL.
